UNITED STATES PATENT OFFICE.

GEORGE A. DESENFANT, OF SAN FRANCISCO, CALIFORNIA.

DESIGN FOR A STICK-PIN.

51,226.

Specification for Design.

Patented Sept. 4, 1917.

Application filed August 29, 1914. Serial No. 859,252. Term of patent 3½ years.

To all whom it may concern:

Be it known that I, GEORGE A. DESENFANT, a citizen of the United States, residing at San Francisco, in the county of San Francisco and State of California, have invented a new, original, and ornamental Design for an Article of Manufacture, of which the following is a specification, reference being had to the accompanying drawing, forming part thereof.

The figure is a front elevation of a stick pin illustrating my design. The invention

may be used for hat pins, scarf clasps or similar articles.

I claim:

The ornamental design for an article of manufacture, as shown.

In testimony whereof, I have hereunto set my hand this 13th day of August, 1914.

GEORGE A. DESENFANT.

Witnesses:

BALDWIN VALE,
A. J. HENRY.
